UNITED STATES PATENT OFFICE.

HARRY LOROANZO CRAIG, OF MIDDLETOWN, NEW YORK, ASSIGNOR OF ONE-HALF TO
WILLIAM PAUL CORBETT, OF MIDDLETOWN, NEW YORK.

SIGNAL DEVICE FOR RAILWAYS.

1,081,892.

Specification of Letters Patent.

Patented Dec. 16, 1913.

Application filed March 1, 1913. Serial No. 751,569.

To all whom it may concern:

Be it known that I, HARRY L. CRAIG, a citizen of the United States, residing at Middletown, in the county of Orange and State 5 of New York, have invented certain new and useful Improvements in Signal Devices for Railways; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this specification. 15

This invention relates to new and useful improvements in automatically operated apparatus for actuating emergency brakes upon railway trains and comprises a simple 20 and efficient device of this nature having various details of construction and combinations and arrangements of parts which will be hereinafter fully described, shown in the accompanying drawings and then specifically defined in the appended claims. 25

I illustrate my invention in the accompanying drawings, in which:—

Figure 1 is a view in elevation showing the application of my invention to a railway 30 and signal tower. Fig. 2 is a plan view of a railway tower and connections adapted to be raised by a railway locomotive. Fig. 3 is a view in elevation of the mechanism carried by the engine and adapted to actuate the 35 emergency brake. Fig. 4 is an enlarged detail view of the brake actuated mechanism, and Fig. 5 is a detail perspective view of the rock shaft and connections for actuating a signal.

Reference now being had to the details of the drawings by letter, A designates a lever adapted to actuate an emergency brake of any desired construction, and B is a longitudinally movable bar which is connected at 40 one end to said lever and is movable between the guides C, and D is a cam which is curved and tapers longitudinally and is adapted to have a wedging or pushing action against the end of the bar B in order to impart a 45 longitudinal movement thereto for the purpose of driving the bar to the position shown in dotted lines in Fig. 4 by which movement the lever for operating the emergency brakes is actuated. Said cam D has arms E integral therewith and which project from a col-

lar F which is pivotally mounted upon a pin H. A bar K has its upper end inverted L-shaped as at K' and normally engages a notch L formed in the convexed edge of the cam D to hold the latter normally in the 60 position shown in solid lines in the drawings. The lower end of the bar K has a cross-piece N, and O is a lever pivotally mounted upon a fixed pin Q, the lever O being adapted, when turned upon its pivot to 65 the position shown in dotted lines in Fig. 4, to cause the bar K to be raised sufficiently to disengage its upper end from the notch in the cam D, thus allowing the latter to fall to the position shown in dotted lines in Fig. 70

4. The falling movement of said cam will tend to impart a longitudinal movement to the bar B and through its connections with the emergency lever to cause the brake mechanism, not shown, to be operated.

Pivotally mounted transversely to the track of the railway in the manner illustrated in Fig. 2 is a rock shaft T mounted in the bearings T' and to the crank arm T² of said shaft a rod T³ is connected which in 80 turn is pivoted at T⁴ to one arm of the angle lever S. A rod S' is pivoted at S² to one arm of the angle lever S and its other end is adapted to actuate the semaphore signal J mounted upon the tower J'.

In operation, when it is desired to set the crank shaft so that it will operate the brakes automatically as the engine equipped with the apparatus passes by the crank shaft, semaphore is set to the position shown in 90 Fig. 3, in which the crank shaft T will project above the rails. The normal position of the lever O is that shown in solid lines in Figs. 1 and 4 and in which position it is adapted to contact with the rock shaft T 95 which, as the engine passes by the same, throws the lever to the position shown in dotted lines, which will raise the bar K and release the cam D, allowing the same to fall to the position shown in dotted lines. The 100 momentum of the cam D in swinging downward is sufficient to impart a longitudinal movement to the bar B which will instantly apply the emergency brakes.

By the provision of an apparatus embodying the features of my invention, it will be noted that a simple and efficient mechanism is afforded whereby a signal may be given to an approaching train equipped with the apparatus and mechanism set in order to au- 110

tomatically apply brakes in the event of the signal not being noticed by the person in control of the brake mechanism in the cab of the locomotive.

5. What I claim to be new is:—

1. An automatically-operated emergency brake apparatus, comprising a brake lever, a bar connected therewith, a pivotal curved tapering weighted cam engaging the end of said bar, a longitudinally movable releasing bar normally engaging and holding said cam, a lever adapted to actuate said bar, a rock shaft adapted to trip said lever and impart a longitudinal movement to the releasing bar to allow said cam to swing downward to move the bar connected to the valve brake lever, as set forth.

2. An automatically-operated emergency brake apparatus, comprising a brake lever, a bar connected therewith, a pivotal curved tapering weighted cam engaging the end of said bar, a longitudinally movable bar having its upper end angled and normally engaging a notch in said cam, a lever pivoted below the lower end of said angled bar, a rock shaft adapted to engage said lever to

impart a longitudinal movement to the bar with an angled end to allow said cam to swing downward and move the bar connected to the valve lever, as set forth.

30

3. An automatically-operated emergency brake apparatus, comprising a brake lever, a bar connected therewith, a pivotal curved tapering weighted cam engaging the end of said bar, a longitudinally movable bar having its upper end angled and normally engaging a notch in said cam, a lever pivoted below the lower end of said angled bar, a rock shaft adapted to engage said lever to impart a longitudinal movement to the bar with an angled end to allow said cam to swing downward and move the bar connected to the valve lever, a signal, and connections between the same and said rock shaft, as set forth.
